UNITED STATES PATENT OFFICE

124,289

DESIGN FOR A TEXTILE FABRIC

Samuel R. Brodie, Bronx, N. Y.

Application November 13, 1940, Serial No. 96,533

Term of patent 3½ years

To all whom it may concern:

Be it known that I, Samuel R. Brodie, a citizen of the United States, residing at the Bronx, Bronx County, and State of New York, have invented a new, original, and ornamental Design for a Textile Fabric, of which the following is a specification, reference being had to the accompanying drawing, forming part thereof, wherein the figure is a plan view of a textile fabric showing my new design.

I claim:

The ornamental design for a textile fabric, substantially as shown.

SAMUEL R. BRODIE.
